Primary Examiner — Dana K Weiland*Assistant Examiner* — Emily Anna Saunders(74) *Attorney, Agent, or Firm* — Jerold I Schneider; Schneider IP Law(57) **CLAIM**

The ornamental design for a smart rope handle, as shown and described.

DESCRIPTIONFIG. 1 is a top, front and right side perspective view of a smart rope handle showing my new design;
FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion 9 in FIG. 1.

The broken lines in the drawings illustrate portions of the smart rope handle which form no part of the claimed design. The broken line circle in FIG. 1 and in the enlarged view of FIG. 9 forms no part of the claimed design.

The diagonal lines in the drawings represent reflective surfaces.
